UNITED STATES PATENT OFFICE.

SAMUEL M. LANGSTON, OF WENONAH, NEW JERSEY, ASSIGNOR TO SAMUEL M. LANGSTON COMPANY, OF CAMDEN, NEW JERSEY, A CORPORATION OF NEW JERSEY.

SHEET-FEEDING MECHANISM.

1,242,356.

Specification of Letters Patent.

Patented Oct. 9, 1917.

Application filed July 25, 1914. Serial No. 853,012.

To all whom it may concern:

Be it known that I, SAMUEL M. LANGSTON, a citizen of the United States, and a resident of Wenonah, in the county of Gloucester and State of New Jersey, have invented certain new and useful Improvements in Sheet-Feeding Mechanism, of which the following is a specification.

This invention relates to certain improvements in mechanism for feeding successive sheets from a column or stack to a machine or apparatus which receives and operates upon the sheet, and relates more particularly to that type which delivers the sheets from the top of the stack or column, and at the same time raises the stack so that the top of the stack will always be at approximately the same elevation.

In its preferred embodiment it is designed for the feeding of comparatively stiff sheets of light material such for instance as paper board, cellular board, or the like, although in certain of its embodiments, it is applicable to the feeding of thin wooden boards, or thin sheets of paper, metal, or other material. The feeding mechanism may be employed in connection with any kind of an apparatus desired such as a printing press, an embossing press, or a cutting or scoring machine.

One of the main features of my invention involves the mechanism which advances a sheet from the top of a column solely by engaging with the rear edge of the top sheet. Other features involve the elevating mechanism and the means for operating the feeding and elevating mechanism in proper time and at the proper relative speeds. The invention involves various other features of importance, all of which will be more particularly described hereinafter, and pointed out in the claims.

Reference is to be made to the accompanying drawings illustrating merely one embodiment of my invention and in which similar reference characters indicate corresponding parts in the several views.

Figure 1 is a side elevation of a feeding mechanism constructed in accordance with my invention, and illustrated as applied to a printing press.

Fig. 2 is an end view of the feeding mechanism.

Fig. 3 is a side elevation, similar to a por-

tion of Fig. 1, but on a somewhat larger scale.

Fig. 4 is a top plan view of the feeding mechanism a portion being broken away, and;

Fig. 5 is a detailed view of the sheet feeding member.

As previously stated, I have illustrated my invention in connection with a printing press of a type designed for printing on relatively stiff paper board or cellular board. Such a press, if desired, may be constructed substantially as shown in my prior Patent 1,086,722, granted February 10th, 1914. I have not here illustrated the details of the press as such details form no portion of my present invention and my improved feeding mechanism may be used in connection with various other forms of presses or other machines.

The specific embodiment of my invention as illustrated in the accompanying drawings includes two frame members 10, 10 which may be secured rigidly in respect to the frame of the main machine or may be cast integral as a part of the latter. The frame members 10, 10, adjacent their outer ends may be supported by or secured to posts or standards 11, 11, extending a considerable distance above the plane in which it is desired to feed sheets to the main machine the purpose of which upper extensions will be set forth more fully hereinafter. For supporting the stack or column of sheets to be fed I may provide any suitable form of platform which may if desired be the platform or body of a truck upon which the sheets are transported to the machine. Adjacent to the outer ends of the frame members 10, 10, I mount two small pulleys 12, 12, and adjacent to the inner ends of the frame members are two additional pulleys 13, 13. Supported preferably by the main frame of the machine is a shaft 14 having two winding drums 15, 15 thereon and from each drum extends two cables, wires, ropes, chains or other flexible members 16 and 17, hereinafter referred to as cables. The cables 16 extend over the pulleys 13 and 12, while the cables 17 merely extend over the pulleys 13. Thus the free ends of the four pulleys are at approximately the four corners of a rectangle and may be secured to the four corners of the column supporting platform.

90

95

100

105

As shown, the cables 17 are connected to a transversely extending bar in the form of an I-beam 18, while the cables 16 are provided with rings 19 adapted to receive the 5 ends of a transversely extending bar 20. These two bars 18 and 20 may detachably engage beneath the opposite ends of the column supporting platform. By rotating the drum it will be noted that the four 10 cables may be unwound or wound up simultaneously, and the column lowered or raised while maintaining the sheets substantially horizontal.

The specific means which I preferably 15 employ for raising or lowering the column may be operated either by hand or automatically during the operation of the machine. This means may include a shaft 21 mounted adjacent to the outer end of one of the 20 frame members 10, and continuously rotated from the main machine in any suitable manner as for instance, by a drive chain 22 extending over a sprocket wheel on the shaft 21 and over a second sprocket 25 wheel of the same size on one of the main shafts of the machine. The power is transmitted from the shaft 21 to the shaft 14 of the winding drums at such a rate as to insure the automatic and intermittent raising 30 of the column to maintain the top in substantially the same plane irrespective of the thickness of the sheets going to make up the column.

The shaft 14 is illustrated as being provided 35 with a beveled pinion 24 meshing with a beveled pinion 25 on a counter shaft 26 extending lengthwise of the machine. This counter shaft has a worm wheel 27 engaging with a worm 28 on a second counter 40 shaft 29. This last mentioned counter shaft carries a ratchet wheel 30, a hand wheel 31, a loosely mounted lever arm 32, carrying a pawl 33 engaging with the teeth of the ratchet wheel. The shaft 21 carries 45 a part presenting an eccentric surface for reciprocating the crank rod. As shown, this part is in the form of a crank pin projecting from a crank arm 34 connected to the shaft. The crank rod engages with the lever arm 50 32 whereby as the shaft 21 rotates, the rod 35 is moved back and forth substantially longitudinally and causes the lever arm 32 to swing back and forth. The teeth of the ratchet wheel are so designed, that during 55 the movement of the arm 32 in one direction, the ratchet wheel is caused to rotate while during a movement in the reverse direction, the ratchet wheel may remain at rest and the pawl slip over the teeth. A 60 separate pawl may be provided for preventing the return rotation of the ratchet wheel, although due to the fact that a return rotation is effectively prevented by the worm and worm wheel such a separate pawl is 65 not ordinarily necessary.

In operating the machine, I give the crank 34 such a throw and the ratchet wheel such a diameter that one rotation of the crank shaft 21 and the resulting partial rotation of the ratchet wheel will effect a 70 winding of the cables on the drum an amount sufficient to raise the column the thickness of one sheet. To permit the handling of sheets of different thicknesses, I provide means for accurately adjusting the 75 machine to vary the relative speeds of rotation of the winding drum and the shaft 21. This I preferably do by varying the throw of the crank 34. As shown the crank is provided with a groove 37 in its outer face 80 and within this groove is slidably mounted a block 39 carrying a crank pin to which the crank rod 35 is pivotally connected. A screw 40 is held against longitudinal movement in an end flange 41 on the crank and is 85 threaded through the block 39 so that by rotating the screw, the block 39 with the crank pin, may be moved toward and from the axis of the shaft 21. With the block in one limiting position, that is with the crank pin 90 in alignment with the axis of the crank shaft, there will be no crank throw and no endwise movement of the crank rod 35. The farther the block 39 is moved away from crank shaft, the greater will be the crank 95 throw and the greater will be the angular advancement of the ratchet wheel and drum for each rotation of the crank shaft. It is evident that other adjusting means might be employed for varying the crank throw in 100 place of the specific one shown.

For feeding the sheets from the top of the column I provide one or more arms 43 suspended from a shaft 44 connecting the upper ends of the posts 11, 11. The lower 105 ends of these arms 43 terminate above the column of sheets and each has secured to its lower end, a second arm 45 extending substantially horizontally toward and beyond the rear edge of the sheets of the 110 column. Secured to each arm 45 is a sheet removing member 46 preferably in the form of a hook pivotally secured to a collar 47 adjustable lengthwise of the arm 45. The hooks are mounted to swing in vertical 115 planes so that their free ends may rest directly upon the top of the column. Each hook has a shoulder 48 to catch the edge of the top sheet and adjusting means for varying the effective width of the shoulder in accordance with the thickness of the sheets to be removed from the column. For instance a thin spring plate 49 may be secured to the lower side of the hook with its free edge adjacent the shoulder 48. A screw 50 may extend down through the body of the hook and engage with the spring to force its free end toward the edge of the shoulder and thus 120 reduce the effective width of the shoulder so that it will engage with the edge of only 125 130

the top sheet of the column and feed a single sheet at a time.

The collars 47 may be secured to the arms by set screws 51 or in any other suitable manner so that they may be adjusted lengthwise, and brought to the proper position to just pass beyond the rear edge of the top sheet when the arms 43 are swung rearwardly. If the arms 43 be sufficiently long 10 and the length of the feeding movement be comparatively short, the arms 45 may be rigid with the arms 43.

Various different means may be provided for swinging the arms 43, but preferably a 15 shaft 55 is mounted in suitable bearings at the upper ends of the posts 11, 11 and is driven by a chain 56 connecting two sprockets of equal size, one on the shaft 55, and the other on the crank shaft 21. On the 20 shaft 55 may be mounted a cam 57 engaging with an arm 58 pivoted on the shaft 44, so that for each rotation of the shaft 55, the two arms 43 will be swung toward the body of the main machine and then released and 25 permitted to swing back by gravity. Return movement might be secured by a spring if desired or a cam might be employed which would effect positive movement in both directions. Two separate cams may be employed one for each arm 43, and the arms 58 may be made integral or rigid with the arms 43 or a single arm 58 might be employed to rotate and shaft 44 and the arms 43 might be rigidly secured to the latter. 30 These are merely questions of machine design, and the desired results may be accomplished by various different mechanisms. Preferably the arms 43 are adjustable toward and from each other to facilitate the 35 feeding of sheets of various widths.

In the operation of the machine, power is transmitted from the main machine to the crank shaft 21 the latter preferably being given one complete revolution for each complete operation of the machine on one sheet. 45 In a printing press, the crank shaft 21 would be rotated once for each rotation of the main impression cylinder. Each rotation of the crank shaft 21 effects a forward and back 50 movement of the sheet feeding hooks or members 46, and also effects one comparatively small winding movement of the drums, thus the feeding mechanism will advance successive sheets from the top of the column to the 55 printing press, one sheet being advanced for each rotation of the impression roller and for each sheet removed from the top of the column, the column itself will be raised a distance equal to the thickness of the sheet. 60 Preferably the feeding movement of the members 46 is at substantially the same rate or at a slightly slower rate than the feed rollers of the main machine. In starting the machine the column may be readily 65 raised by hand by turning the hand wheel

31 which is mounted on the shaft 29. This hand wheel may be provided with a crank handle and due to the interposition of the worm gearing one man may easily turn this wheel comparatively rapidly to raise the 70 column to the desired position.

When it is desired to lower the column or the empty platform the pawl 33 may be swung over to inoperative position and the hand wheel readily turned in the opposite 75 direction without transmitting motion to the sheet advancing mechanism or the main working parts of the machine.

It will be noted that the frame members 10, 10, are not only spaced apart but that 80 there are no shafts or other connecting members between the two except on the body of the machine and at the upper ends of the posts 11, 11. This permits trucks carrying stacks of sheets to be wheeled directly between the two frame members and into the proper position to facilitate the securing of the cables to the platform or other support for the column. 85

I wish it particularly understood that the 90 specific machine illustrated in the accompanying drawings and hereinbefore described constitutes only one embodiment of my invention and that various changes in details and the relative arrangement of the 95 parts may be made within the spirit of my invention and without departing from the scope of the appended claims.

Having thus described my invention, what 100 I claim as new and desire to protect by Letters-Patent, is;

1. Sheet feeding mechanism including a support for a column of sheets, a substantially vertical arm above said column, a second arm secured to the lower end of said 105 first arm, a collar adjustable along the length thereof, a hook pivoted to said collar and adapted to engage with the edge of the top sheet on said column and means for swinging said first arm to cause said hook 110 to engage with and laterally displace the top sheet.

2. Sheet feeding mechanism including a support for a column of sheets, a substantially vertical arm above said column, a second arm secured to the lower end of said first mentioned arm and normally disposed substantially parallel to and directly above 115 said column of sheets, a collar adjustable along the length of said second mentioned arm, a hook pivoted to said collar and adapted to engage with the edge of the top sheet of said column, and means for swinging 120 said first arm to cause said hook to engage with and laterally displace said top sheet. 125

3. Sheet feeding mechanism, including a support for a column of sheets, a rod normally disposed substantially parallel to and directly above 130 said column of sheets, means

for reciprocating said rod, a collar adjustable along the length of said rod, and a hook pivoted to said collar and adapted to engage with the edge of the top sheet of said column 5 for laterally displacing said top sheet upon the reciprocation of said rod.

4. Sheet feeding mechanism, including a support for a column of sheets, a substantially vertical arm above said column, means 10 for swinging said arm, a rod secured to the lower end of said arm and normally disposed substantially parallel to and above said column of sheets, a collar secured to

said rod, and a hook pivoted to said collar and adapted to engage with the top sheet of 15 the column to laterally displace said top sheet upon the swinging movement of said arm in one direction.

Signed at New York city, in the county of New York and State of New York, this 18th 20 day of July, A. D. 1914.

SAMUEL M. LANGSTON.
